UNITED STATES PATENT OFFICE.

FRANK SILVA, OF COPPERHILL, TENNESSEE.

MILL.

Application filed November 21, 1925. Serial No. 70,594.

To all whom it may concern:

Be it known that I, FRANK SILVA, a citizen of the United States, residing at Copperhill, in the county of Polk and State 5 of Tennessee, have invented certain new and useful Improvements in Mills, of which the following is a specification, reference being had to the accompanying drawings.

This invention relates to mills and more 10 particularly to the type of mill employed for reducing rock, ores and the like and employing rollers for the purpose of such reduction.

An important object of the invention is 15 to provide a mill employing internal classification of the materials being reduced and removing from the mill such portions of the materials as have been reduced to the desired size.

20 A further object of the invention is to provide a mill having means whereby this internal classification may be accomplished during operation of the mill.

A still further object of the invention is 25 to provide a mill, the construction of which embodies the combined advantages of the ball or pebble type mill with that of the roll type mill and in this combination reducing the amount of power necessary to 30 operate the mill and eliminating the necessity for returning to the mill after discharge therefrom such portions of the materials as have not been properly ground thus adapting the roll type mill for use in the 35 finer grinding operation ordinarily performed by the ball or pebble type mill.

A further and more specific object of the 40 invention is to provide a mill employing wet classification for internal separation of the coarse particles from the finer particles and for removing these finer particles from the mill.

These and other objects I attain by the 45 construction shown in the accompanying drawings, wherein for the purpose of illustration is shown a preferred embodiment of my invention and wherein:—

Figure 1 is a side elevation of a mill constructioned in accordance with my invention;

Figure 2 is a sectional view showing one of the supports and the shaft mounting;

Figure 3 is a horizontal sectional view through the mill;

55 Figure 4 is an enlarged detail sectional

view showing the manner of applying the ring liner to the mill;

Figure 5 is a vertical sectional view illustrating the operation of the interior of the mill;

Figure 6 is a view of the intake end plate;

Figure 7 is a similar view of the exhaust end plate.

Referring now more particularly to the drawings, the numeral 10 indicates a circular casing having at one side an internal frusto-conical flange 11 forming one side wall of the mill and providing a central axial opening 12 forming the intake of the mill. To the opposite side of the casing 10 is secured a frusto-conical flange 13 forming the opposite side wall of the mill and an axial discharge opening 14 of slightly greater diameter than the intake opening 12.

The flanges 11 and 12 have secured thereto annular tracks 15 and 16 of the same external diameter and co-axial with the casing. These tracks rest upon supporting and guiding rollers 17 permitting rotation of the casing but preventing downward movement thereof.

As a means of attaching the tracks 15 and 16, the smaller end of the flange 11 is provided with an inturned attaching flange 18 to which the track 15 is secured while the flange 13 is formed in two sections 80 13^a, 13^b having at their adjacent edges flanges 19 between which a web 20 formed upon the track 16 is engaged and secured.

The casing section 10 is likewise formed in two sections bolted together upon the web 90 21 of a gear 22 which is preferably of the herring-bone, as illustrated. This gear is engaged by a suitably driven pinion 23 serving as a means for rotating the casing.

A ring liner 24 is provided for the central 95 casing section 10, this liner being secured in position by opposed web blocks 25 connected by bolts 26 as a means for drawing them toward one another, these web blocks coacting with the tapered faces 27 formed upon the outer surface of the ring liner.

Suitable linings 28 and 29 are bolted or otherwise secured, as at 30, upon the interior of the flanges 11 and 13 to protect the same. 100 Arranged in opposition to the discharge and intake ends of the completed casing are suitable supports 31 upon the upper ends of which are mounted inverted U-shaped guide yokes 32. Each guide yoke has slidably mounted therein a pair of upper and 105

110 lower guide blocks 33, 34 which are secured to the yokes 32 by bolts 35. The upper blocks 33 are secured to the casing 10 by bolts 36, the lower blocks 34 being secured to the yokes 32 by bolts 37.

lower blocks 33 and 34, the upper block being engaged by adjusting screws 35 extending through the bight of the U-shaped frame member and heavy coil springs 36 being arranged upon the blocks. Thus means are provided for yieldably forcing the lower block 34 downwardly. The blocks 34 receive the ends of parallel members 37 which extend through the intake and discharge openings of the casing and are provided interiorly of the casing with spaced yoke frames 38 each having at each end thereof a depending arm 39. Between the lower ends of adjacent arms are mounted crushing rollers 40, 40^a which, by the tension of the springs 36, are forced into engagement with the ring liner 24. By their mounting, the adjacent faces of these rollers are separated from one another to provide a space 41, the purpose of which will hereinafter appear.

The yokes at their upper surfaces form a mounting for an internal feed launder 42. This launder inclines from end to end, the lower end of the launder being arranged above the roller 40 beneath which a given portion of the ring liner 24 first passes during rotation of the mill. Adjacent the upper end of this launder, a spray pipe 43 is disposed directing a spray of water into the upper end of the launder to cause the contents thereof to be washed from the discharge end and to pass between the roller 40 and the ring liner. Above the roller 40^a, a second spray pipe 44 is arranged, this spray pipe directing a spray of water downwardly and outwardly toward the surface of the ring liner 24 so that the direction of this spray is partially in opposition to the direction of rotation of the ring liner and casing. The direction of rotation of the casing is indicated by the arrow on Figure 5.

The bars 37 at each end of the casing provide mountings for end plates 45, 46 closing or substantially closing the intake and discharge openings 12 and 14 respectively. The plate 45 is formed in upper and lower sections 45^a, 45^b, hingedly connected to one another, as at 47. Means are provided, as at 48, for locking the plates in alignment with one another, such means being removable to permit the upper section 45 to be swung downwardly, permitting access to the mill. The lower section 45^b is rigidly secured to the bars 37. The upper section 45^a has formed therein an opening 49 for the passage of a feed launder 50 and a water pipe 51 which, interiorly of the mill, is branched to produce the spray pipes 43 and 44. The plate 46 is similarly constructed from the upper and lower sections 46^a, 46^b hingedly connected, as at 52, and having removable means, as at 53, for holding the sections in aligned relation. The lower section 46^b is rigidly secured to the bars 37 and has a portion of its lower edge cut away, as at

54, to provide an opening for discharge of liquid and suspended reduced material from the casing. Beneath this opening, a discharge launder 55 is arranged exteriorly of the casing.

In the operation of the mill above described, assuming the mill to be rotating in the direction of the arrow on Figure 5 and material being fed through the mill feed launder 50, this material, upon reaching the launder 42, is washed down the launder and passes successively between the rollers 40 and 40^a and the walls of the ring liner 22. The crushing pressure of these rollers, will, of course, reduce a certain portion of the material thus fed to the desired size and this reduced material will be more or less in the suspension of the liquid fed into the mill. At the relatively quiet space provided between the rollers 40 and 40^a, the heavier particles are permitted to precipitate so that they lie against the ring liner while the lighter particles will pass out with the overflow at the discharge opening 54 and so to the discharge launder. Of course, a certain portion of this finer reduced material will cling to the heavier particles and be carried thereby between the rollers 40^a and the liner. This causes a further reduction of the heavier particles and this reduced material is met by the spray 44 which washes the lighter particles permitting them to return to the space 41 and pass to the discharge opening. The heavier particles will, by centrifugal force, pass the spray 44 and moving upwardly with the casing will only leave the same when this force is expended. The speed of rotation of the mill is such that this takes place at a point where the heavier particles fall upon the upper end of the launder 42, as illustrated in Figure 5 and are washed down with the incoming feed to pass between the roller 40 and the liner. It will be obvious that the pressure placed against the material may be regulated by regulation of the feed screws 35 and that by this regulation greater force may be exerted against the roller 40 or 40^a, as is found desirable. Since a substantially uniform pressure is maintained by the rollers against the casing to urge them into engagement with their trackways, the operation of the mill is smooth and the fluctuations and power demand are much smaller than those ordinarily occurring in the usual type of mill used for the finer grinding operation.

The structure hereinbefore set forth is obviously capable of a certain range of change and modification and I, therefore, do not limit myself to such specific structure except as hereinafter claimed.

I claim:—

1. In a mill, a casing having external trackways, rollers engaging said casing and

supporting the casing for rotation, means for rotating the casing, the casing having at its opposite ends feed and discharge openings, spaced supports projecting through the feed and discharge openings, means for yieldably forcing the supports downwardly, crushing rollers carried by the supports within the casing and means for maintaining a constant fluid level within the casing.

2. In a mill, a casing, means for rotating the casing, the casing having at its opposite ends feed and discharge openings, supports projecting through the feed and discharge openings, crushing rollers carried by the supports within the casing and engaging the interior of the casing at points spaced at opposite sides of the bottom center of the casing and fluid means for classifying the contents of the casing within the casing.

3. In a mill, a casing, means for rotating the casing, the casing having at its opposite ends feed and discharge openings, supports projecting through the feed and discharge openings, crushing rollers carried by the supports within the casing and engaging the interior of the casing at points spaced at opposite sides of the bottom center of the casing and a launder carried by the supports and inclined to deliver material between the inner wall of the casing and the roller which is in advance as regards the direction of rotation of the casing and means for maintaining a constant fluid level within the casing.

4. In a mill, a casing, the casing having at its opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing and means for rotating the mill at a speed such that unreduced material will be deposited in the upper end of said launder by gravity.

5. In a mill, a casing, the casing having at its opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, means for rotating the mill at a speed such that unreduced material will be de-

posited in the upper end of said launder by gravity and means for maintaining a constant fluid level in the casing.

6. In a mill, a casing, the casing having at the opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, means for rotating the mill at a speed such that unreduced material will be deposited in the upper end of said launder by gravity and means for spraying said material after its passage beneath the last named roller to thereby separate therefrom material which has been reduced.

7. In a mill, a casing, the casing having at its opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, means for rotating the mill at a speed such that unreduced material will be deposited in the upper end of said launder by gravity, means for maintaining a constant fluid level in the casing and means for delivering a spray against the material after its passage beneath the other of said rollers at a point above the fluid level in the casing and in a direction opposite to the direction of travel of the material.

8. In a mill, a casing, the casing having at its opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, means for rotating the mill at a speed such that unreduced material will be deposited in the upper end of said launder by gravity, and means for delivering a spray to the upper end of the launder to wash the material from the lower end thereof.

9. In a mill, a casing, means for rotating the casing, the casing having at its opposite ends feed and discharge openings, supports

projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, and means for maintaining a constantly augmented body of fluid within the casing whereby to provide wet classification of the contents of the casing and to withdraw lighter particles of the materials from the discharge opening thereof.

10. In a mill, a casing, means for rotating the casing, the casing having at its opposite ends feed and discharge openings, supports projecting through the feed and discharge openings, crushing rollers carried by the supports within the casing and engaging the interior of the casing at points spaced at opposite sides of the bottom center of the casing and means for feeding material into the casing between the inner wall of the casing and the roller which is in advance as regards the direction of rotation of the casing receiving unreduced material after 25 its passage beneath the other of the rollers and delivering it to the first named roller.

11. In a mill, a casing, means for rotating the casing, the casing having at its opposite ends feed and discharge openings, sup-

ports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing and fluid means for classifying the contents of the casing during rotation of the casing.

12. In a mill, a casing, the casing having at its opposite ends feed and discharge openings, supports projecting through the feed and discharge openings, crushing rollers carried by the supports within the casing and engaging the interior of the casing at points spaced at opposite sides of the bottom center of the casing, a launder carried by the supports and inclined to deliver material between the inner wall of the casing and the roller which is in advance as regards the direction of rotation of the casing, means for rotating the mill at a speed such that unreduced material will be deposited in the upper end of said launder by gravity and means for classifying the contents of the casing during rotation of the casing.

In testimony whereof I hereunto affix my signature.

FRANK SILVA.
